Assistant Examiner — James T Tyree

(57) **CLAIM**

The ornamental design for a toy, as shown and described.

DESCRIPTION

FIG. 1 is a front left perspective view of a toy showing a first embodiment of my new design thereof;

FIG. 2 is a front view of the toy shown in FIG. 1;

FIG. 3 is a back view of the toy shown in FIG. 1;

FIG. 4 is a left side view of the toy shown in FIG. 1;

FIG. 5 is a right side view of the toy shown in FIG. 1;

FIG. 6 is a top-down view of the toy shown in FIG. 1; and,

FIG. 7 is a bottom view of the toy shown in FIG. 1.

The broken lines are included for the purpose of illustrating portions of the toy and form no part of the design.
